ANNEALING APPARATUS

Clarence B. Hoak, Stenbenville, Ohio

Application September 29, 1937, Serial No. 166,430

5 Claims. (Cl. 268—5)

The present invention relates generally to annealing apparatus, and is a continuation in part of my co-pending application Serial No. 66,932, filed March 3, 1936, and entitled Annealing furnace structure, and relates particularly to the heat treating of sheet steel and tin in a manner insuring proper distribution of the heat to the top, bottom and sides of the material during the treatment, and in a manner to positively prevent oxidizing of the material under treatment; and an important object of the present invention is to provide annealing structure of the character indicated wherein the construction may be sectional or integral so as to facilitate the handling of the furnace itself and its efficiency in operation.

Another important object of the present invention is to provide annealing apparatus of the character indicated wherein portions thereof are portable to increase the mobility and utility in increasing the productivity thereof.

Another important object of the present invention is to provide improvements in structure and function over the subject matter contained in the mentioned pending application, in the respects of more efficient circulation of and use of the heating gases and products of combustion, in the adjustability of the partitions forming the combination and annealing chambers, respectively, whereby by a simple adjustment the flow of the heating gases may be changed in accordance with requirements.

Another important object of the present invention is to provide improvements over the subject matter of the said pending application, in the respects of greater accessibility and simplicity of manufacture and operation of the furnaces.

Other important objects of the present invention will be apparent from a reading of the following description taken in connection with the drawings, wherein for purposes of illustration I have shown preferred embodiments of the present invention.

In the drawings—

Figure 1 is a side elevational view of a form of the invention which is generally elongated rectangular in plan and is provided with a hood having straight vertical longitudinal walls and straight squared end walls terminating at their upper edges in a relatively slightly curved top which curves from side to side, upper and lower rows of burner openings being provided for alternate use in the opposite longitudinal sides of this embodiment.

Figure 2 is an end elevational view of Figure 1.

Figure 3 is a view of an embodiment of the invention similar to that shown in Figure 1 and differing therefrom only by reason of the provision of removable straps extending between the base and the hood and enabling transporting the furnace combination of hood and base from place to place as may be needed.

Figure 4 is an enlarged horizontal sectional view taken through Figure 1 approximately on the line 4—4 and looking downwardly in the direction of the arrows.

Figure 5 is an enlarged transverse vertical sectional view taken through Figure 1 approximately on the line 5—5.

Figure 6 is a fragmentary view similar to Figure 5 but showing the hood raised from the base.

Figure 7 is a fragmentary view similar to Figure 6 but showing the partitions in raised adjusted positions, these partitions being shown in depressed positions in Figure 5.

Figure 8 is a group horizontal sectional view taken through a portion of one of the partitions showing the solid elements composing the same.

Referring in detail to the drawings, the numeral 5 generally designates the hood of the furnace which may have an arch-shaped cross section as shown or assume any other suitable size and shape and be composed of an outer metal shell 6 having a hoisting handle at the middle of its top. The lower edge of the shell has a laterally inwardly extending flange 8 which rests on a similar flange 9 on the upper edge of the peripheral wall on the base 10 so that the hood is thereby separably assembled on the base and may be lifted therefrom. In some cases the hood may be connected to the base in some suitable manner such as indicated in Figure 3 of the drawings whereby the base is lifted along with the hood. Upper and lower burner openings 11 are distributed along the side walls of the hood, any suitable number of burner openings being provided according to requirements.

The hood has its interior lined with suitable refractory material structure, the walls of which are severally and respectively designated by the numerals 13, 14, 15 and 16.

As illustrated the present furnace shows two partitions 17, 17 which are spaced from the side-walls 15, 16, respectively, and extend between the end walls 13, 14 of the hood, thereby defining the combustion chambers, and the annealing chamber between the partitions.

Each partition is composed of a number of tiers exemplified by the vertically succeeding sections

- 18, 19 and 20 and 20' in each tier, and a desirable number of tiers is used in each partition 17, the tiers being juxtaposed and interlocked in a manner to be pointed out.
- 5 Each tier section is of heat resisting metal or of refractory material suitable to radiate and conduct heat from the combustion chamber to the material being heated, and constituted by a triangular cross section body 21.
- 10 One end of the annealing chamber wall 15' of each of the sections is pointed as indicated by the numeral 35 while at the opposite end the adjoining side wall of the section is notched as indicated by the numeral 36, both formations extending the full height of the respective section.
- 15 The points 35 are engaged with the notches 36 in juxtaposing and assembling the various tiers of sections to form the respective partitions 17. The bottom of the lowermost sections are squared 20 to stand squarely on the base when the partitions are lowered, while the upper ends of the uppermost tier sections are angulated to conformably engage the top of the hood when the partitions are elevated.
- 25 The base 10 has within the annealing chamber defined by the end walls 13 and 14 and the partitions 17 has thereon the longitudinally arranged annealing stands 40 and 41 between which is arranged a row of vertical exhaust outlet openings 39 with similar rows of exhaust openings at the outer sides of the stands adjacent the partitions as indicated. Any suitable number of stands may be used with corresponding obvious rearrangements and enlargements of the base 30 and hood structure described. Each annealing stand or platform 40, 41 is composed of suitable material in the form of a plate 42 from which depend conical legs 43 which space the plate 42 above the floor of the base and permit free circulation of the gases under the plate 42.
- 35 Imposed on each stand is the respective cover 44, 45 enclosing a respective stack (not shown) of the sheet material being treated and annealed, wherein each cover is provided on its sides with downwardly tapering flanges 48 which have attached to the outer lower edge thereof the sand retaining rim 49 which retains a quantity of sand or the like to prevent passage of any air or fluid between the top of the stand and the 45 interior of the cover, thereby preventing the possibility of any oxidizing of the contents of the cover.
- 40 Attention is called to the fact that the line of separation between the hood and the base 55 is on a level which passes through lower side wall burner openings which are located above the floor level of the base, so that the burners may be attached either to the upper or hood half of the burner opening or to the lower or base half of the 50 burner opening as may be found desirable.
- 45 The base comprises a shallow pan-shaped shell whose floor, end walls and sidewalls are lined with refractory material, the lower halves of the lower burner openings being formed in the upper edges of the sidewalls.
- 55 The tier forming sections of the partitions are provided with a vertical bore 22 to receive the supporting rod 55 which has on its lower end a head 56 socketing in the lowermost section of the respective tier and having its upper end threaded as indicated by the numeral 57 and passing through a tube 58 in the transversely curved hood 5 on the top of which a nut 59 is threaded on the threaded portion 58 in the manner disclosed in Figure 5. The topmost sections

of the tiers are beveled as indicated by the numeral 60 to conform to the contour of the inner surface of the curved top of the hood to provide a gas passage there while the lower ends of the tiers are resting on the floor of the base 10. 5

In the embodiment of the invention shown in Figure 7, all of the structure present in the embodiment already described is present in the same, the only difference between Figure 5 and Figure 7 being the adjustment on the partition 17 10 to an elevated instead of a depressed position and the provision of a spacing sleeve 61 resting on the top of the tube 58 and engaged at its upper end by the nut 59 so as to bring the beveled top 60 of the tier to engagement with the top 15 of the furnace hood and to bring the lower end 61 of the tier into vertically spaced relation with the floor of the base so as to define a gas passage.

The longitudinal side walls 15 and 16 of the 20 hood are provided with horizontal rows of upper burner openings 64 and 65. Below these rows of burner openings are the burner openings 11 which are half in the base and half in the lower edge of the hood 5. The exhaust openings are 25 arranged in three rows through the base, one row being between the stands 40 and 41 and the others being at the laterally outward sides of the stands and between them and the partitions 17. The plugs 66 and 67 are placed in the upper 30 burner openings 64 and 65 when the partitions are in the depressed positions shown in Figure 11. In the elevated positions of the partitions the burners are shifted to the elevated openings 64 and 65 and the plugs 66 and 67 shifted to the 35 lower burner openings 11 to plug the same.

Figure 6 of the drawings graphically shows the various positions of the parts when the hood 5 is raised from the base 10 with the partitions 17 in the depressed position.

The embodiment of the invention shown in Figure 3 differs from that shown in Figure 1 only by the provision of straps 70 which are secured by removable bolts 71 to the hood and to the base, for connecting the hood and base together to be transported as a unit.

Although I have shown and described herein preferred embodiments of my invention, it is to be definitely understood that I do not desire to limit the application of the invention thereto, 50 and any change or changes may be made in the materials and in the structure and arrangement of the parts, within the spirit of the invention and the scope of the subjoined claims.

Having described the invention, what is 55 claimed as new is:

1. Annealing apparatus comprising a generally rectangular base, a similarly rectangular hood resting on and enclosing said base, upper and lower rows of burner openings in two opposite side walls only of said hood, plugs for shutting off either the upper or lower row of burner openings while the other row is in use, a vertically adjustable partition adjacent each of said opposite side walls of the hood and dividing the space defined by the interior of the hood and the top of the base into a single centralized annealing chamber between the partitions and two combustion chambers running along the opposite sides of the apparatus, said partitions being 60 vertically adjustable to space the same from the hood or the base in accordance with the row of burner openings in use.

2. Annealing apparatus comprising a generally rectangular base, a similarly rectangular hood 75

resting on and enclosing said base, upper and lower rows of burner openings in two opposite side walls only of said hood, plugs for shutting off either the upper or lower row of burner openings while the other row is in use, a partition adjacent each of said opposite side walls of the hood and dividing the space defined by the interior of the hood and the top of the base into a single annealing chamber located between the partitions and two combustion chambers running along the opposite sides of the apparatus, said partitions being shorter than the distance between the base and the top of the hood, and means suspending the partitions from the top of the hood and enabling adjusting the partitions to rest on the base or engage the top of the hood.

3. Annealing apparatus comprising a generally rectangular base, a similarly rectangular hood resting on and enclosing said base, upper and lower rows of burner openings in the longitudinal side walls only of said hood, plugs for shutting off either the upper or lower row of burner openings while the other row is in use, a longitudinal partition adjacent each side wall of the hood and dividing the space defined by the interior of the hood and the top of the base into a single annealing chamber located between the partitions and two combustion chambers running along the opposite sides of the apparatus, the upper ends of the partitions being spaced below the top of the hood, the lower row of burner openings being open and the upper row closed by the plugs, and means suspending the partitions from the top of the hood and enabling adjusting the

partitions to engage the top of the hood and be spaced at their lower ends from the base.

4. Annealing apparatus comprising a base formed with exhaust openings, a removable hood resting on the base, longitudinally extending vertical partitions at opposite sides of the hood and dividing the space defined by the hood and base into a centralized annealing chamber and two combustion chambers, said exhaust openings being in communication with said annealing chamber, means secured to depend from the top of said hood and traversing said partitions and holding said partitions in place, said means being adjustable to vary the spacing of the upper and lower ends of the partitions from the top of the hood and the base, respectively.

5. Annealing apparatus comprising a base formed with exhaust openings, a removable hood resting on the base, longitudinally extending vertical partitions at opposite sides of the hood and dividing the space defined by the hood and base into a centralized annealing chamber and two combustion chambers, said exhaust openings traversing the floor of said annealing chamber, rods depending from said hood and traversing said partitions and holding said partitions in place, the longitudinal side walls of said hood being formed with upper and lower rows of individually closable burner openings, means on said hood for adjusting said rods to permit the lower end of the partitions to rest upon said base or to engage the upper end of the partitions with the top of the hood.

CLARENCE B. HOAK. 35
